UNITED STATES PATENT OFFICE.

JACOB KOENIG, OF JERSEY CITY, NEW JERSEY.

DESIGN FOR A SHRINE OR NICHE FOR STATUARY.

SPECIFICATION forming part of Design No. 24,727, dated October 1, 1895.

Application filed August 8, 1895. Serial No. 558,682. Term of patent 3½ years.

To all whom it may concern:

Be it known that I, JACOB KOENIG, a citizen of the United States, residing at Jersey City, in the county of Hudson and State of New Jersey, have invented and produced a new and original Design for a Shrine or Niche for Statuary or other Articles, of which the following is a specification, reference being had to the accompanying drawings, showing a part thereof.

The object of this invention is to provide a handsome and ornamental niche or shrine which presents a characteristic and distinguishing appearance to the eye.

15 The design consists in a niche or shrine having its back provided with central and angle ornaments, and with a base or offset portion and a frame portion connected to the back by a plaiting or ruffle-surface.

20 The design is illustrated by the accompanying drawings, in which—

Figure 1 is a face view of the niche or shrine, and Fig. 2 is a horizontal sectional view of the same.

25 In the drawings, the numeral 1 indicates the back or sunken portion of the niche having a central ornament resembling a crown 2 and wreath 3 and the angular or shield or-

naments 4 and the angular or flower ornaments 5. A base or offset portion is shown 30 at 6.

The frame part of the shrine is indicated at 7 and is connected to the back of the shrine by a filling 8, consisting of a plaiting or ruffle-surface. The frame 7 is inclined 35 rearward from its meeting line with the filling 8. This filling is inclined or contracted from said meeting line toward the back or sunken portion 1. The ornaments 2, 3, 4, and 5 are disposed on the back 1 and project 40 therefrom.

The design provides an ornamental, handsome, and distinctive shrine or niche adapted for the reception of statuary figures or other objects.

45 What I claim as new, and desire to secure by Letters Patent, is—

The design for a niche or shrine substantially as shown and described.

In testimony whereof I have hereunto set 50 my hand in the presence of two subscribing witnesses.

JACOB KOENIG.

Witnesses:
